UNITED STATES PATENT OFFICE.

SAMUEL HAMMER, OF BROOKLYN, NEW YORK, ASSIGNOR TO UNITED METAL BOX CO INC., OF LONG ISLAND CITY, NEW YORK, A CORPORATION OF NEW YORK.

LOCK-ATTACHING MEANS.

Application filed July 13, 1926. Serial No. 122,089.

This invention relates to lock attaching means, and has for its primary object to provide simple and inexpensive means for quickly and securely attaching a lock to the door or closure of a mail box or other receptacle but which, in the event that the lock should become broken or for other reasons fail to operate, will permit of the detachment or removal of the lock without mutilation of the door structure and the substitution of a new lock in its place.

Locks of the character generally used upon doors of mail boxes or receptacles, are of simple construction and relatively inexpensive. Heretofore, if the door was locked and the locking mechanism was out of order so that the door could not be opened, in order to remove the lock from the inner side of the door, it has been necessary to cut away the door plate, since in the modern type of such mail receptacles, the hinge connection between the door and the body structure of the receptacle is inaccessible. Consequently, it was necessary not only to provide a new lock, but an entire new door. These box doors are constructed of heavy sheet brass, and are more or less expensive so that such replacement of an entirely new door for the mail box compartment resulted in a material addition to the initial cost thereof. The locking device however, being comparatively cheap, in case said device is totally destroyed in its removal from the door, it can be replaced at a fraction of the cost of a new door.

In one practical embodiment of my present invention whereby the above purpose is attained, a reinforcing plate of sheet steel is securely fixed to the inner face of the door. I provide this plate adjacent one of its ends with yieldable tongues struck from the plane thereof and suitably spaced lugs. The lock case is positioned between these lugs and has its side walls disconnected from the end walls of the case and provided with apertured ears to receive said tongues. After the lock has thus been applied, the tongues are forced under pressure from their normal positions and caused to bear against the edges of the apertures in said ears so that the side walls of the lock case are sprung outwardly from their normal positions and into tight abutting contact

between the spaced lugs. In this manner, the lock case will be rigidly held or fixed in position on the inner side of the door and with the lock barrel receiving projection on the front of the case disposed in a suitably formed opening in the door structure. Should it become necessary to remove the lock and substitute a new one therefor while the door is in locked position, by means of a suitable tool sufficient pressure is exerted against the cylindrical lock barrel casing to force the lock bodily away from the inner face of the door, said ears riding against the yieldable tongues and forcing said tongues back to their former positions. Of course, in removing the lock in this manner, the lock bolt which projects into the keeper opening in the body wall of the box will probably be broken or badly distorted and it would not be profitable to attempt to repair the lock. However, by means of said bendable or yieldable tongues, a new lock may be easily and quickly substituted and attached to the door.

In another embodiment of my invention, I may provide a relatively thin plate of sheet metal having its marginal portion welded or otherwise secured to the inner face of the door its intermediate portion spaced therefrom and provided with a slot to receive suitable attaching bolts for the lock case. The headed ends of the bolts are positioned between said plate and the inner face of the door, and by applying the necessary pressure against the outer side of the lock, said metal plate will yield to such pressure, the bolt heads being forced through the slot, the edges of which will be bent or broken. In this case, if it is not possible to straighten said plate for the attachment of a new lock, the plate may be removed from the inner face of the door and a new one substituted therefor.

With the above and other objects in view, the invention consists in the improved lock attaching means for mail box doors or other closures and in the form, construction, and relative arrangement of the several parts thereof as will be hereinafter more fully described, illustrated in the accompanying drawings, and subsequently incorporated in the subjoined claims.

In the drawings, wherein I have illustrat-

ed several simple and satisfactory embodiments of the invention, and in which similar reference characters designate corresponding parts throughout the several views,—

5 Figure 1 is a fragmentary front elevation of a mail box door having a lock applied thereto;

Fig. 2 is a rear elevation showing the attaching means for the lock;

10 Fig. 3 is an enlarged sectional view taken on the line 3—3 of Fig. 2;

Fig. 4 is a sectional view taken on the line 4—4 of Fig. 2;

15 Fig. 5 is a view similar to Fig. 2 showing a slightly modified form of the device;

Fig. 6 is a horizontal section taken on the line 6—6 of Fig. 5, and

Fig. 7 is a view similar to Fig. 5, the lock being detached.

20 Referring in detail to the drawings, and for the present more particularly to Figs. 1 to 4 thereof, the door 5 as herein shown is of a more or less conventional type now commonly used in connection with multi-
25 compartment mail boxes or receptacles designed for installation in office or apartment buildings, hotels and similar structures accommodating a large number of tenants. It is the usual practice to securely
30 attach to the inner face of each compartment door of the mail box adjacent its free end a suitable lock, the bolt of which engages in an opening or mortise provided in the bottom wall of the box structure adjacent
35 its front edge. Such a locking device, I have herein generally indicated at 6. I do not, however, directly attach this lock to the inner face of the door, but there is secured upon the inner face of said door and
40 practically entirely covering the same a reinforcing plate 7 of sheet steel. This plate at the end edge thereof adjacent the free end edge of the door is recessed or cut away as at 8 and at the opposite ends of
45 said recess the lugs 9 are provided and extend at right angles to the plane of the door. Spaced from each of these lugs longitudinally of the plate 7, said plate is provided with a second lug 10 struck from the
50 plane of the plate. Preferably, these latter lugs are separated from the plate only at their inner opposed ends, the other end and side edges thereof remaining integrally connected with said plate, and said lugs being substantially of semi-circular cross sectional form as indicated in Fig. 3 of the drawing.

Between each pair of spaced lugs 9 and 10, tongues 11 are struck from the reinforcing plate 7 so that they normally project
60 from the inner face of said plate at right angles to the plane thereof as shown in dotted lines in Fig. 4.

The door 5 is provided with a circular opening 12 therein for the purpose of receiving the cylindrical projection on the

front wall of the lock case in which the lock barrel is mounted, and as herein shown, the edge of this opening is inwardly turned through a registering opening in the reinforcing plate 7 and bent over the inner face 70 of the latter plate as shown at 13, thus providing a convenient means for attaching the reinforcing plate to the inner side of the door. However, this is not essential and any other desired means may be utilized 75 for this purpose.

The mechanism of the lock 6 is of course, enclosed within a suitable case, and as herein shown the opposite side walls 14 of this lock case are free or disconnected at their 80 opposite ends from the end walls of the case as clearly indicated in Fig. 4 of the drawings and the front longitudinal edges of said side walls are also free or unattached from the front plate 15 of the latch case. On these front longitudinal edges of said side walls 14 at the center thereof, the laterally projecting ears 16 are formed. Each of these ears has an elongated opening or slot 17 therein for the purpose of receiving one of the tongues 11 on the reinforcing plate 7.

In the use of the above described form of my invention, it being understood that normally the side walls 14 of the lock case are in parallel relation with each other and that the tongues 11 in the reinforcing plate 7 project inwardly therefrom at right angles to the plane of the door, the lock is positioned upon the inner side of the plate 7 between the spaced pairs of lugs 9 and 10 and the tongues 11 are engaged through the openings 17 of the respective ears 16. These tongues thus serve as guides, directing the cylindrical lock barrel receiving projection 18 on the front wall 15 of the lock case into the door opening 12. The tongues 11 are now spread apart or forced laterally under pressure to the oblique position seen in Fig. 100 4 of the drawings, and thereby are caused to coact with the outer edges of the slots 17 and exert an outward lateral pressure against the ears 16, thus expanding the side walls 14 of the latch case outwardly and simultaneously drawing the case bodily into tight contacting engagement with the inner face of the plate 7 and causing said side walls 14 of said case at their opposite ends to tightly abut against the lugs 9 and 10. It will therefore, be apparent that the lock case will be very rigidly fixed and held in its applied position against all ordinary forces which might tend to displace the lock in the use of the structure to which it is applied.

Assuming that the lock bolt is in its projected locking position thus holding the door closed and preventing access to the receptacle compartment, and that for some reason the lock mechanism fails to operate when

the proper key is inserted so that the bolt cannot be retracted, it then becomes necessary to entirely remove the lock from the door. This may be readily done by applying 5 a suitable tool against the outer end of the cylindrical extension or housing 18 of the lock barrel and by the application of several hammer blows, causing sufficient inward pressure whereby the ears 16 will ride 10 against the yieldable tongues 11 and return said tongues to their former normal positions thus enabling the ears to be readily disengaged therefrom. In this manner, it will be seen that the lock in its entirety may 15 be very readily detached from the door without in any way marring or mutilating the door structure. Also, a new lock may be as readily substituted for the one removed in the manner above explained and without 20 necessitating that the door shall first be detached at its hinged end from the box structure.

In Figs. 5 to 7 inclusive, I have shown an alternative form of my present improvements wherein a relatively light sheet metal plate 19 is stamped by suitable dies to provide an offset marginal portion 20 adapted to be welded or otherwise securely fixed to the inner face of the door. Thus, it will be 25 understood that the body portion 21 of this plate is spaced from the inner face of the door. This body portion of the plate is provided with a circular opening 22 therein to coincide with the opening in the door plate 30 which receives the cylindrical barrel housing of the lock case and is also formed with slots 23 extending horizontally from the opposite sides of said opening.

The lock case is adapted to be applied 40 with its front wall engaged against the body 21 of the plate 19, the front wall of said case having flanges 24 apertured to receive attaching bolts 25. These bolts at one of their ends are provided with enlarged circular heads 26, the peripheries of which are preferably rounded or convex as shown in Fig. 6 of the drawings and adjacent to the head 26, a rectangular portion 27 is formed upon the shank of the bolt for engagement 45 in one of the slots 23 whereby the attaching bolts will be held against turning or rotative movement. Nuts 28 are threaded upon the ends of said bolts and are adapted to be adjusted for tight clamping engagement 50 against the flanges 24 whereby the lock case is rigidly held in fixed relation to the plate 19. It will of course, be understood that the attaching bolts may be first readily applied 55 by positioning the heads 26 thereof through the opening 22 of the plate 19 then moving said bolts into the respective slots 23 with the bolt heads positioned between the plate 19 and the door plate. In this construction, whenever it becomes necessary to remove the 60 lock, the necessary pressure is applied so

that the relatively thin metal plate 19 will yield, and the bolt heads 26 will be forced through the slots 23. These bolt heads are of course, of greater diameter than the width of said slots so that in thus forcing said bolt 70 heads through the slots the edges of said slots will be distorted and possibly broken. However, if necessary the plate 19 can be readily replaced at small expense in comparison with the cost of an entirely new 75 door.

From the foregoing description considered in connection with the accompanying drawings, the construction, manner of use and several advantages of the illustrated embodiments of my invention will be clearly understood. It will be seen that I have devised very simple and inexpensive means for attaching the lock to the door which is entirely inaccessible when the door is closed 80 and locked but which, nevertheless, admits of the complete detachment of the lock without mutilating or defacing the door structure. For reasons which will be apparent, the disclosure contained in Figs. 1 to 4 of 85 the drawings is preferred, since it is most economical both as to the initial cost and maintenance thereof. However, in some cases where the projecting tongues 11 might be found objectionable, the construction last 90 described may be employed. Also, in addition to these two constructions to which I have specifically referred, it will be apparent that the essential features of this invention are susceptible of embodiment in other 95 alternative structures. Accordingly, it is to be understood that I reserve the privilege of resorting to all such legitimate changes in the form, construction and relative arrangement of the several parts as may be 100 fairly incorporated within the spirit and scope of the invention as claimed.

I claim:

1. In combination with a closure member having an opening therein, a lock attaching element secured to the inner side of said closure member, said opening adapted to receive an outwardly projecting part of a lock arranged at the inner side of the closure member, and said attaching element and the lock 110 case having coacting relatively yieldable means to yieldably retain the lock in its applied position, and said yieldable means yielding upon the application of inward pressure against said outwardly projecting part of the lock whereby the lock may be 115 forcibly detached from the closure member.

2. In combination with a closure member having an opening therein, a lock adapted to be mounted upon the inner side of said closure member provided with a part 120 to project through said opening, a plate secured upon the inner side of the closure member and having parts yieldable under pressure, and means connected with the lock 125 130

case coacting with said yieldable parts to retain the lock in its applied position, and said parts yielding to an inward pressure applied against said outwardly projecting part of the lock whereby the lock may be forcibly detached from the closure member.

3. In combination with a door having an opening therein, a lock adapted to be mounted on the inner side of the door and provided with a part to project through said opening, spaced lugs on the inner side of the door between which the lock is adapted to be positioned, the lock case having outwardly yieldable side walls opposed to said lugs, members projecting from the inner face of the door and yieldable under pressure, each of said side walls of the lock case having means with which said members are adapted to be forced into coacting engagement to expand the side walls of the latch case outwardly into abutting contact with said lugs, and said members yielding under an inward pressure applied against said projecting part of the lock to thereby forcibly detach the lock from the door.

4. In combination with a door having an opening therein, a lock adapted to be mounted on the inner side of the door provided with a part to project through said opening, a plate fixed to the inner side of the door and having spaced yieldable projections between which the lock is adapted

to be positioned, and the side walls of the case being provided with apertured parts 35 with which said projections coact to fixedly retain the lock in its applied position, and said projections yielding under an inward pressure applied against said outwardly projecting part of the lock whereby the lock 40 may be forcibly detached from the door.

5. In combination with a door having an opening therein, a lock adapted to be mounted upon the inner side of the door provided with a part to project through said opening, 45 the lock case having outwardly yieldable side walls and said reinforcing plate provided with spaced pairs of lugs between which the lock case is adapted to be arranged, said plate also having spaced yieldable tongues struck therefrom and said side walls of the latch case provided with apertured ears to receive said tongues whereby when said tongues are bent under pressure in one direction, the side walls of the latch 55 case are expanded into abutting engagement against said lugs, and said tongues adapted to yield to an inward pressure applied against said projecting part of the lock to forcibly detach the lock from the 60 door.

In testimony that I claim the foregoing as my invention, I have signed my name hereto.

SAMUEL HAMMER.
